UNITED STATES PATENT OFFICE.

JOHN BATEY, OF DUBLIN, IRELAND.

MANUFACTURE OF WIRE SPOKES FOR WHEELS.

SPECIFICATION forming part of Letters Patent No. 602,931, dated April 26, 1898.

Application filed October 2, 1897. Serial No. 653,783. (No model.)

To all whom it may concern:

Be it known that I, JOHN BATEY, a subject of the Queen of Great Britain, residing at 47 Heytesbury street, Dublin, Ireland, have invented certain new and useful Improvements in Machinery for Straightening and Dividing Wire into Lengths Applicable Especially for the Manufacture of Wire Spokes for Wheels, of which the following is a specification.

10 The object of this invention is to provide automatic mechanism for straightening and dividing wire into lengths suitable for wire spokes for wheels. The drawings hereunto annexed show the machine I have devised for 15 effecting this object.

In this machine the wire to be straightened is led in a zigzag course between pins which project up from a curved surface, which gives to the wire a definite curvature. Afterward 20 the wire is led in a zigzag course over and under rollers which take out this curvature, and then through an eye or eyes for its end to be seized by a gripper on a sliding carriage. The movable jaw of the gripper is actuated by 25 toggle-levers. The central joint of the toggle-levers is coupled by a connecting-rod to an oscillating lever. As the lever oscillates it opens and closes the gripper and moves the slide to and from the eyes above mentioned.

30 When the slide is at the end of its travel nearest to the eyes, the next movement of the lever closes the gripper and causes it to seize the wire and then moves the sliding carriage forward, the gripper drawing forward the wire 35 along with it. A definite length of wire is so drawn forward and passed between cutters. At the end of the forward stroke the cutters are caused to commence to cut the wire. The next backward movement of the lever first 40 opens the gripper and then moves back the carriage. The cutters then complete their cut and the same operations are repeated.

Figure 1 is a side elevation, and Fig. 2 an end view, of the machine. Fig. 3 is a side elevation, and Fig. 4 an end view, of the curved surface over which the wire is first led. Fig. 5 is an end view, on a larger scale, of dies used for holding the wire and acting to some extent as a draw-plate hole after the wire has 45 been straightened. Fig. 6 is an end view with cover-plate removed, and Fig. 7 a longitudinal section of the sliding carriage and gripper

carried by it. Fig. 8 is an end view, and Fig. 9 a plan, of the cutting mechanism. Fig. 10 is an end view, and Fig. 11 a horizontal section, on an enlarged scale, of the cutting mechanism.

A is a drum having wound around it the wire to be straightened.

B is a brake-block carried by a lever-arm 60 on an axis B' and made to bear down upon the wire by the weight B², carried by another lever-arm on the same axis.

C is a fixed curved surface having pins C' projecting from it in a zigzag line. C² is a 65 guide carried at the lower end of this surface.

C³ is an eye through which the wire is led after passing over the guide.

D D' D' are flanged rollers under and over which the wire is led. The first roller 70 D' can be raised or lowered, so as more or less to deflect the wire from a straight line as it passes below and over the rollers D.

E is a fixed block having an eye or hole 75 formed through it of a size to fit the wire closely and of sufficient length to take out any short sharp bends which may still remain in it.

F F are two half-dies carried by a block F' and which nip the wire between them. The 80 lower one is fixed and the upper one pressed down toward it by a lever F², acted on by a spring F³.

G G are two half-dies mounted on a sliding carriage H. The upper die is fixed to the 85 carriage. The lower one can be slid toward or away from the upper die.

G' are toggle-levers jointed at their upper end to the lower die G and at their lower end to a fixed point on the carriage.

G² is a link passing from the central joint of the toggle-levers to the upper end of a lever-arm J. This arm can be rocked on the axis J' at its lower end by a connecting-rod K, passing from it to a crank-pin projecting 95 from a disk L, which is fast on the main or driving shaft M. The crank-pin can be slid along a radial slot in the disk and set nearer to or farther from the shaft to adjust the extent of movement given to the lever.

N is a roller on the lower end of a vertical slide on the carriage H. It is pressed downward by a spring N', and when the carriage is at the end of its traverse nearest to the dies

If it enters a hollow in a bracket-piece O and tends to retain the carriage in this position, but can yield if sufficient force is exerted to move the carriage along its guides.

5 P P are the cutters for severing the wire, (marked X in Figs. 10 and 11,) and Q an eye through which the wire is led just before passing to the cutters. Preferably the cutters are formed, as shown at Figs. 8 and 9, of two small rings through which the wire passes. One ring P lies in a corresponding recess in the end face of the block Q', by which the eye Q is carried, the other in a recess in the face of a lever P', which turns on a fulcrum at P². 15 The two rings are held together face to face by the lever being held up toward the end of the block Q' in the manner shown. One end of the lever P' is weighted with a weight P³. The other is coupled by a connecting-rod P⁴ with one arm of a lever R, another arm of which carries a truck or roller R', which rests on a cam S on the main shaft M. The cam I form in such manner that the cutters commence to partially cut the wire just as the 25 sliding carriage H completes its forward movement, and they complete their cut just before the carriage commences its next forward movement. The ring which lies in the recess in the block Q' has a hole in the center 30 a little larger than the wire to be cut and the other a much larger hole. The holes are somewhat eccentric to one another. A slight tendency is thereby given to the rings to make a partial turn at each cut. The whole edge of 35 the central hole in each ring is thereby made available as a cutting edge, each portion of the edge being at one time or another brought into action.

What I claim is—

- 40 1. The combination of a drum upon which the wire to be straightened is wound, a brake bearing on the wire, a curved surface with pins projecting from it in zigzag course over which the wire is first led to bend the wire in one direction, the rollers for subsequently bending the wire in the opposite direction, the gripper carried by a slide, the toggle-levers for actuating the gripper, the rod jointed to
- 45

the central joints of the toggle-levers, and mechanism for giving a to-and-fro end-way movement to this rod so as when the rod is moved in one direction to first close the gripper and then move the slide endwise to draw the wire forward through the straightening appliances, and when the rod is moved in the opposite direction to first open the gripper and then move the slide backward, and the cutter for cutting off a length of wire which projects beyond the gripper.

2. The combination of wire-straightening appliances, the gripper, the slide by which it is carried, the toggle-levers, the to-and-fro end-way-moving rod, jointed to the central joints of the toggle-levers, the cutter, and mechanism for causing the cutter to partially cut through the wire when the slide completes its forward movement and to complete the cut just before the slide commences its next forward movement.

3. The cutter formed of two rings held together, face to face, and capable of being moved one over the other, and both free to turn while in action, substantially as described.

4. The combination of the curved surface over which the wire is first led, the bending-rollers through which the wire next passes, and mechanism for first closing the gripper onto the wire and then moving it endwise to draw the wire forward and afterward to open the gripper and then move it backward.

5. The combination of the curved surface with pins projecting from it in a zigzag course, over which the wire is first led to bend the wire in one direction, the rollers for subsequently bending the wire in the opposite direction, the gripper, the slide by which it is carried, the toggle-levers, the to-and-fro end-way-moving rod jointed to the central joint of the toggle-levers, and the cutter for cutting off lengths of wire after they have been drawn forward by the gripper.

JOHN BATEY.
